UNITED STATES PATENT OFFICE

JOHN M. AUFIERO, OF BROOKLYN, NEW YORK, ASSIGNOR TO E. A. LABORATORIES, INC.,
OF BROOKLYN, NEW YORK, A CORPORATION OF NEW YORK

DESIGN FOR A HORN OR SIMILAR ARTICLE

Application filed April 26, 1930. Serial No. 35,403. Term of patent 14 years.

To all whom it may concern:

Be it known that I, JOHN M. AUFIERO, a citizen of the United States, residing at Brooklyn, in the county of Kings and State of New York, have invented a new, original, and ornamental Design for Horn or Similar Article, of which the following is a specification, reference being had to the accompany-

ing drawings, forming a part thereof, where-in—

Fig. 1 is a perspective view of a horn; and Fig. 2 is a side view thereof.

I claim:

The ornamental design for a horn or similar article, as shown.

JOHN M. AUFIERO.
